ELMER M. JONES, OF ATLANTA, GEORGIA, ASSIGNOR TO JONES SIGNAL SYSTEM COMPANY, OF ATLANTA, GEORGIA, A CORPORATION OF GEORGIA.

CLOSED-CIRCUIT SIGNAL SYSTEM.

1,126,775.

Specification of Letters Patent.

Patented Feb. 2, 1915.

Application filed April 8, 1908. Serial No. 425,821.

To all whom it may concern:

Be it known that I, ELMER M. JONES, a citizen of the United States, residing at Atlanta, in the county of Fulton and State of Georgia, have invented a certain new and useful Improvement in Closed-Circuit Signal Systems, of which the following is a full, clear, and exact description, reference being had to the accompanying drawings.

10 The object of this invention is to provide a simple and efficient electric signal system adapted to give an indication in a moving locomotive or vehicle whenever the track ahead is obstructed or broken.

15 Among the characteristics of this invention may be mentioned certainty of operation, simplicity and durability, and comparatively small cost both in original equipment and maintenance. To insure the certainty of operation referred to, the system is composed of normally closed circuits, the opening of which operates the signal, so that any breakage of the conductors will show a danger signal. As the track itself 20 constitutes a portion of one of the normally closed circuits, any breakage of the rail or an open drawbridge will cause the danger signal to be exhibited. The same is true of an open switch.

25 In its preferred form, my installation includes a normally closed system on the locomotive with appropriate signals or other means operated thereby, a track divided into blocks and a normally closed electric system therefor. The track system for a single track road where trains run in both directions is composed, for each block, of: first, a main normally closed circuit, including a portion of the track, a relay, a source 30 of current, and conductors; second, two line circuits, each controlled by the main circuit relay, one for the block at one end of that under consideration, and the other for the block at the other end, each line circuit having conductors, a source of current, a magnet, and being controlled also by a locking relay hereinafter mentioned; third, two locking relays for each block, each of which controls the corresponding line circuit, each 35 locking relay being provided with two magnets and two circuits for operating them, which circuits may be controlled by a passing locomotive; fourth, two contact plates for each block adapted for connection with 40 a locomotive, and a connection from such

contact plate to the track controlled by the corresponding line magnet and preferably also by the locking relay. The main circuit, the line circuits and the locking circuits are normally closed and each provided with 45 sources of current, while the contact plate connection is normally open. For a double track installation, where the trains run only in one direction, the locomotive system is the same, while in the track installation, 50 the locking relays and circuits are omitted, and the main magnet may directly control the connection from the contact plates to the rails, there being, in this instance, only one contact plate for each block instead of two. 55

The invention is herein illustrated in the form of diagrams.

Figures 1^a and 1^b show the complete wiring of a block and so much of the two adjacent blocks as cooperates therewith, this diagram being made in two sections, the lower portion (Fig. 1^b) being supposed to join at its left hand end with the right hand end of the upper portion (Fig. 1^a). Fig. 2 is a simplified view of a central block and 60 two adjacent blocks, the intermediate portion of the central block where the rails and conductors are simply continuous being broken out. In each of these diagrams the main circuits for protecting the block are 65 shown in heavy lines and the locking circuits to prevent trains from entering the block at the same time from opposite ends are shown in light lines. Fig. 3 is a diagram of the locomotive circuit. Fig. 4 is a 70 simplified diagram of the same.

The locomotive circuit, as shown in Fig. 4, includes a battery 1, a magnet 2, and lines 3 and 4 which are ordinarily connected by a movable member 5. The magnet and battery are thus in a normally closed circuit which operates to hold the signal at safety, this signal being indicated by a pivoted blade 6 which is shown as counterweighted at 7 to give it a tendency to swing into the horizontal or danger position, the shaft of the signal being connected by a link 8 with a movable armature 9 for the magnet, this armature being illustrated as a central rod passing through the magnet which may be 80 made in the form of a solenoid. This embodiment is shown simply by way of example and is adapted to illustrate any signal which may be held at safety by a magnet and which automatically moves to dan- 85 90 95 100 105 110

ger when the current through the magnet ceases. A branch line 10 leads from the normally closed circuit 3 and 4 to the frame, axle and wheels of the locomotive. The member 5 is shown as mounted on a slideable rod 11 carried by the frame and terminating in a contact brush 12. A spring 13 maintains the brush in position normally with the circuit closed at 5. It will be seen from this locomotive circuit that if the brush 12 runs over an elevated contact plate, the closed circuit 3 and 4 will be broken at 5 and that hence the signal will go to danger unless another line is provided completing the circuit via the brush, contact plate and through the rails and track system to the locomotive wheels. As will be hereinafter seen, my track system does provide such a path for the current whenever the track is clear, but not when it is obstructed or broken.

I will now proceed to describe the track system by reference to the simplified diagram Fig. 2, it being understood that between the two broken lines in this figure the two rails and the two conductors shown continue uninterruptedly for the distance of a block. The main track circuit includes the two rails X X', at least one of which is sectional, being divided into blocks, designated A', A², A³, by suitable interposed insulation indicated by 22. It is advantageous to have both rails sectional to prevent interference by foreign currents, but my system is operated with only one rail sectional and such is the form shown in the simplified diagram Fig. 2. As shown, there are three of these blocks, and the sectional rail is further broken by small sections c', d' and e'. These sections are for the purpose of controlling the locking circuits referred to and need not now be described. Suitable conductors 28 form bridges around these short sections, so that for the purpose of the main circuits the sectional rail is broken only between adjacent blocks. Considering now block A², there will be seen near one end of the block a battery 30 on a line 31 leading from the sectional rail to the continuous rail. Near the other end of this block is a line 32 passing from the continuous rail through a magnet 33 and from this magnet a line 34 leads to the sectional rail. It will thus be seen that there is normally a closed main circuit with a battery leading from the magnet 33 and including substantially the entire length of the sectional rail in the block. The magnet 33 is adapted to hold an armature 40 in position to close two circuits which lead in each direction from the block A². These circuits I denominate line circuits. One of these circuits is composed of a line 41 which leads through an armature 42 normally in contact therewith to the continuous rail near the adjacent end

of block A³. The other portion of this circuit consists of a line 44 leading from the armature 40 through a battery 45 and through a magnet 46 to the continuous rail. This circuit is thus normally closed and employs as a part of itself a part of the continuous rail. The other circuit comprises the line 50 connected with the sectional rail of block A² and the line 51 which leads through a magnet 52, line 53 which leads through a battery 54 to an armature 55 which is connected by a line 56 with the sectional rail of block A² near its other end. The magnet 52 in this circuit is accordingly on a closed circuit through a battery, such closed circuit including as a part of itself the sectional rail of block A². The line magnets 46 and 52 each operate to hold in normally closed position armatures 47 and 57 respectively, which form connections from contact plates 48 and 58 to lines 49 and 59 which lead to the respective rails. Now with the circuits as described, if a locomotive approaches block A² from block A', the brush 12 runs on to the contact plate 48. This action opens the circuit 3 and 4. Now if block A² is unoccupied, the circuit opened at 5 on the locomotive is immediately replaced by a circuit leading from the brush to the contact plate to the armature 47, line 49 to the continuous rail, through the wheels of the locomotive to the line 10, and accordingly the signal on the locomotive remains at safety. A corresponding result takes place if the locomotive approaches from block A³ when its brush engages plate 58. If, however, there is a train standing on block A², the result is that such train short circuits the main battery 30, deenergizing the main magnet 33 and opening the two line circuits controlled thereby, which deenergizes the line magnets 46 and 52, breaking the connection from the contact plates 48 and 58 to the rails. In such condition, with the brush on the locomotive running onto plate 48 or 58, the locomotive circuit would be broken at 5 and would not be replaced by another circuit, so that the signal on the locomotive would at once go to danger. The same result would follow from a breakage in either of the rails of the block A² or from the opening of a drawbridge therein. Any switch in that block is also arranged so that the opening thereof either short circuits the battery 30 or opens the circuit. Furthermore, any breakage of either the main or line circuit lines themselves would, of course, leave the circuits open and cause a danger signal.

It will be seen that the system so far described is adequate to protect trains from either direction entering an occupied or broken block. It is essential, however, to lock each block before a train enters it so that another train shall not come into the 130

block in the interim between the time the first train tests the block to see if it is clear and actually enters the block. Otherwise, two trains running in opposite directions 5 might enter an intermediate block which was otherwise clear and collide in that block. It is furthermore desirable that the testing of each block be made at a suitable time and distance before the block is entered 10 and that the locking of the block take place before such test is made and continue after the test until the testing train occupies the block. For this purpose I provide what I call a locking circuit, which is shown in 15 lighter lines than the main circuits described. I will first describe this locking circuit by reference to the simplified diagram Fig. 2. The line circuits, via the lines 41 and 53, include as essential elements the 20 armatures 42 and 55, by which I mean that the armatures may cause a break therein. Each of these armatures is controlled by a double acting relay, designated in Fig. 2, R' for block A² and R² for block A³. It is 25 to be understood that the relay R² for the armature 42 is similar to that for the armature 55. I will accordingly describe the latter. The relay R' for the armature 55 includes a pair of magnets 60 and 61, which 30 tend to draw in opposite directions on the armature 55. The magnet 60, it will be seen, is on a closed circuit including lines 63, 64, and 65, connected with a portion of the continuous rail and a short section d' of the 35 sectional rail. This circuit passes through a battery 67. The result is that the magnet 60 is normally energized and holds the armature in position to keep the circuit closed. This action of this magnet is opposed by a 40 spring 69 and also by a magnet 61. Magnet 61 is on a normally closed circuit, consisting of the lines 70, 71, 72, 73, the portion of the continuous rail between the lines 71 and 73, connected with the short portion c' 45 of the sectional rail in block A², and the portion c' of sectional rail in block A³. In this circuit is a battery 75. It is to be understood that the locking circuit in block A³ controlling the armature 42 and extending 50 over into the adjacent end of block A² is similarly arranged. It is omitted in Fig. 2 for clearness. Now, with the circuits described, suppose trains are approaching block A² from blocks A' and A³. The first 55 train to reach the contact plate 48 or 58, as the case may be, would receive no signal, because the block A² is unoccupied; but before the train reaches such contact block, it encounters the locking circuit referred to. 60 We will consider the train on block A'. When the wheels of this train engage the rail section c', the battery 75 is short circuited, but no change results, for the armature is already held by the magnet 60. 65 When, however, these wheels engage the rail section d', they short circuit the magnet 60 and allow the spring 69 to pull the armature over to the magnet 61, breaking the circuit through the magnet 52. This opens the circuit from contact plate 58 to the sectional rail, so that the train approaching on block A³ would get a danger signal when the brush contacted with the plate 58. The same result would happen to the train on block A' if the train on block A³ had 70 reached the locking circuit when the train on block A' engages the plate 48. Thus whichever train gets to its contact plate first receives a clear signal. The other train receives a danger signal. As the train on 75 block A' passes onto block A², its wheels engage the short rail section c' and thereby short circuit the battery 75, which releases the armature 55 and allows the magnet 60 to draw it back into normal position to close 80 the circuit via the armature 55. The main circuit, however, is now open by reason of the wheels of the train short-circuiting the main magnet 83, which keeps the magnets 52 and 46 deenergized and the line from the 85 contact plates 58 and 48 to the rails open, thus setting the danger signal at each end of the occupied block. The train on block A³, when it receives the danger signal may stop or may back out. In so backing out, it operates its own locking circuit, which would open the circuit through the magnet 46 and would then restore that circuit when the train finally cleared the short rails of 90 its own locking circuit. Such operation is 100 immaterial, for the train from block A' has already passed onto block A². This latter train, however, cannot proceed beyond block A², for before it reaches the end of this block it engages the contact plate appurtenant to block A³, and would receive a signal via the main lines, as already described. It will be seen therefore that the 95 operation of the locking circuit is to lock the block at the far end before any train 105 approaching from the other end can either test the block or enter it; that such locking at the far end continues until the train has entered the block and that shortly after the train enters the block, the lock which was 110 established by the locking relay is released, but before such release, the block becomes 115 protected at each end by means of the main relay and the two line relays. The train does not therefore receive a danger signal 120 from its own operation or from anything behind it, but continuously sets the track system in front of it and behind it to give a signal to a train approaching from either direction. With two trains approaching 125 the same block, the one which reaches its locking relay first has the right of way, for it locks the block in advance and receives no danger signal, while the other train does receive a danger signal from the locked 130

block. If the latter train which has thus been stopped gets out of the way, the other train can continue in the next block, otherwise the first train is itself stopped in the intermediate block.

It is to be noted that the short rail sections c' , d' and e' need be only long enough to allow time for making a good contact and the operation of the corresponding magnet.

10 If the section c' were far enough from the section d' so that there would certainly be a train length between them, the spring 69 might be omitted and the magnet 61 relied on to pull the armature in that direction.

15 If these rails e' and d' are close together, the spring is necessary, for both magnets might be deenergized at the same time by the same train. The short rail sections have no coöperation whatever with the locomotive circuit and simply form the exposed portions of the locking circuits, which are bridged by the passing locomotive to cut out the corresponding batteries.

The magnet 60 has a pulling force substantially equal to the combined force of the magnet 61 and the spring 69, but by reason of the armature 55 being normally closed to the magnet 60, that magnet will hold the armature in closed position against the combined pull of the magnet 61 and the spring 69. Accordingly, when the magnet 60 is short circuited, the spring, or the magnet 61, or both, may swing the armature to open position. When the magnet 60 is reenergized, its force is not sufficient to pull the armature away from the magnet 61 when that magnet is energized, but can pull it against the action of the spring 69 when the magnet 61 is deenergized.

40 From the above description it is believed that the complete diagram in Figs. 1^a and 1^b may be very clearly understood. The same reference characters apply to this diagram with exponents according to the number of the block. In this figure both rails are sectional and there are short sections opposite the short sections described. This does not vary the operation described, but avoids any danger of interference by foreign currents.

50 The lines from the various contact plates to the rails are shown as normally open but closed by the back-action of the corresponding double-acting relays. This constitutes a check on the relay, so that if it should not operate a danger signal would be given. Fig. 1^a also shows the main relay or magnet M' applied at the right hand end of the block A' , while Fig. 1^b shows such relay at the right hand end of block A^2 , indicated by

60 M^2 . Additional contact plates 80 and 81 are shown in this diagram, these plates appertaining to block A^2 , and being located adjacent to the far end of such block with reference to a train running thereon. We have supposed a train to enter block A^2

when there was a train standing on block A^3 . If this latter train is still on block A^3 when the train on block A^2 reaches the contact plate 81, this latter train receives a signal after the manner set out. It will thus be seen that each block includes a main magnet near one end of the block, with the circuits described and a battery located near the other end of the block, and two contact plates near the far ends of the block, each of said contact plates being connectible with the track under the control of the main magnets of the two adjacent blocks through the two corresponding line magnets and being controlled also by the double acting relays of the locking circuits beyond the other end of such adjacent block. There are two of these relays for each block, located near the ends thereof, each relay having two short track sections in the block to which it appertains, and a short track section in the beginning of the adjacent block. Each block accordingly has six short track sections, three near each end, two of these three coöperating with the corresponding relay and the third one with the relay of the adjacent block. The relay corresponding to the end of block A' which is adjacent block A^2 is designated R' , and the relay corresponding to the end of block A^3 which is adjacent to block A^2 is called as a whole R^3 , these two relays appearing in both the diagrams. The two relays of block A^2 which are omitted in Fig. 2 are designated R^2 and RR^2 . Similarly the main magnets or relays are designated M' and M^2 , according to the block to which they relate. The short portions of the rail X' , controlling the locking circuits, are correspondingly designated c' , d' , e' , $-c^2$, d^2 , e^2 , $-cc^2$, dd^2 , ee^2 , and c^3 , d^3 , e^3 . Corresponding short portions in the rail X are clear without reference characters.

The track installation above described is that for a single track road where the trains run in both directions and it is for such railways that a block signal system is most needed. For double track roads or for roads where trains run always in the same direction, no locking circuits are necessary and the control of the connection from the contact plate to the track, through the intervention of line relays, may be simplified by allowing the main magnet to control the connection directly. The locomotive circuit may be the same for both single and double track equipment.

I have heretofore described the locomotive circuit with reference to the simplified diagram Fig. 4. Fig. 3 shows a more elaborate form of locomotive circuit which has the following features not appearing in the simplified form, namely: First, the brush is arranged so that it may move idly over the contact plate when the train is moving in the wrong direction; second, a relay is

provided which operates the signal magnet and enables the signal to be continued at danger after being set by the relay until replaced by the engineer; and third, there is a plug jack provided to cause such replacement. These features will now be described. The brush 12 is connected with the rod 11 by a knuckle joint, as indicated in Fig. 3 at 90. A suitable spring 91 keeps the brush 10 normally in place, with a stop shoulder on its head against the bar 11. On movement of the vehicle in the opposite direction, however, (namely, that opposite to the arrow in Fig. 3) the brush may trail idly over the contact plate without raising the bar 11. The relay in the locomotive circuit is designated 93. It has an armature 94 connected with a line 95 from the contact maker 5. This armature is adapted to engage a line 96, which is one of the terminals of the relay magnet, the other terminal line 97 being connected with the solenoid or signal magnet 92. The relay and solenoid magnets are thus in series on a circuit passing 25 through the armature 94 and the contact 5. Accordingly, when the elevation of the brush breaks the contact at 5, the circuit is open between 94 and 96 and the relay magnet and solenoid magnet are deenergized 30 and the signal comes to danger. The signal stays at danger after the brush passes off the contact member and closes the contact 5, for the circuit is still open at the magnet 93. To enable the trainmen to restore the relay 35 in such a way that the signal will remain at danger until the operation of the plug jack has ended, I arrange the plug jack so that it shunts the solenoid magnet 2 whenever it reestablishes the circuit through the relay. As shown, this plug jack consists of a casing 40 carrying an insulating block 101 with two metallic members 102 and 103. A plug 104 is provided for operating the block and a spring 105 for returning it to normal position. Normally, the contact members 102 and 103 are idle, but when the block is pushed in by the plug the contact plate 102 connects the line 95 with the line 98 leading 45 to the line 96, while the block 103 connects the line 99 with the line 109, which together form a shunt about the magnet 2. The operation, therefore, of pushing in the plug is to shunt the magnet 2, leaving the signal at danger, and close the circuit from the battery 1 via the lines 4, 95, 98 through the magnet 93 to the line 97, to the line 99, to the line 109. This reenergizes relay 93, which attracts the armature 94 to close the contact 96. Now when the pressure upon 50 the plug 104 is removed, the spring 105 returns the block 101, opening the shunt 99, 109, and accordingly the battery current flows through the magnet 2 and returns the signal to safety. It will be seen, therefore, 55 that the plug cannot be left in on account

of spring 105 and that as long as it is in, the signal stays at danger; but that the forcing in of the plug and the subsequent return thereof will restore the relay and signal to safety.

Having thus described my invention, I claim:

1. In an electric signal system, the combination of track rails divided into blocks, a magnet connected therewith, contact plates, 75 connections from such contact plates to the rails, a governing relay for each block, a track circuit for operating it by a locomotive in an adjacent block, one of said connections being under the control of said 80 magnet, and also under the control of said governing relay.

2. In an electric signal system, the combination of track rails divided into blocks, a magnet connected therewith, a source of current connected with the rails in the same 85 block, contact plates adjacent to the two ends of the block, connections from such contact plates to the rails, a governing relay, said connections being under the control of 90 said magnet and also under the control of said governing relay, there being a comparatively short contact beyond the end of the particular block which is between said contact plates, and a circuit for operating said 95 relay connected with said short contact.

3. The combination of a track divided in sections or blocks, a magnet, a circuit through the magnet including parts of the track, a source of current for said circuit, 100 two circuits adapted to be maintained normally closed by said magnet, contact plates adjacent to the opposite ends of the block, connections from said contact plates to the track openable by armatures, and magnets 105 for said armatures included in said two circuits, combined with a vehicle, a normally closed signal circuit thereon connected with the vehicle wheel, and a contact brush on the vehicle adapted to engage said contact plates 110 and therupon open the said vehicle circuit and simultaneously connect the same with said contact plates.

4. The combination of a track divided in sections or blocks, a magnet, a circuit 115 through the magnet including a section of the track, a source of current for said circuit, two circuits adapted to be maintained normally closed by said magnet, contact plates adjacent to the opposite ends of the section, 120 connections from said contact plates to the track, armatures for controlling the connections, magnets for said armatures included in said two circuits, two relays respectively connected with the track beyond the opposite ends of the block, said relays also controlling said two circuits.

5. In an electric signal system, the combination of a track, a normally closed vehicle circuit, a normally closed governing circuit 125

including a magnet, a section of rail, a connection to the opposite rail and a source of current, such source of current short circuited when the vehicle engages such section 5 of rail, there being a bridging connection around such section of rail to preserve the electric continuity of the rail, an armature operated by said magnet, a contact plate adapted to be engaged by a terminal of the 10 vehicle circuit, a connection from said plate to the track, and mechanism whereby such connection is under control of said armature.

6. In an electric signal system, the combination of a track divided into blocks, a governing circuit located adjacent to the end of a block and connected with a short section of rail within that block and a short section of rail beyond the block and with part of the opposite rail and adapted to be shunted by 15 a vehicle thereon, a source of current carried by such shunted portion, and a signal controlling line circuit itself controlled by the governing circuit.

7. In an electric signal system, the combination of a track divided into blocks and a governing circuit located adjacent to each end of each block, each such circuit including a relay and being connected with short sections of track both in the block and in 20 the adjacent block, and a signal controlling line circuit, itself controlled by the governing circuit.

8. In an electric signal system, the combination of a track divided into blocks, a normally closed line circuit, a governing circuit located adjacent to each end of each block, each such circuit including a relay and short insulated sections of track respectively in the 25 block and in the adjacent block, and means controlled by one of said relays for opening the line circuit.

9. In an electric signal system, the combination, with a track divided into blocks and a track circuit and a line circuit controlled 30 thereby, of a governing circuit located adjacent the end of each block, said line circuit being controlled by one of said governing circuits, a relay and a short section of track included in such governing circuit, a contact plate, and a connection between it and the track controlled by said line circuit.

10. The combination of a track divided into sections or blocks, contact plates adjacent to the opposite ends of a block, connections from said contact plates to the track 35 openable by armatures, magnets for said armatures, circuits through these magnets, pairs of opposed magnets operating other armatures to open and close the circuits controlling the first mentioned magnets, circuits through these pairs of magnets connected with the track beyond the block for controlling the connections from said contact plates to the track.

65 11. The combination with a track divided

into blocks, of a main track circuit for each block including a portion of the track, a source of current and a relay, two contact plates beyond the opposite ends of such block, connections between such contact 75 plates and the track, magnets for controlling such connections and themselves controlled by such relay, and additional means adapted to be engaged and operated by a locomotive beyond one end of the block for controlling the connection from the contact plate beyond the other end of the block to the track.

12. The combination with a track divided into blocks, of a main track circuit including a portion of the track, a magnet and a source of current all arranged on a closed circuit, the source of current being adapted to be shunted by a vehicle on such block, contact plates located beyond the opposite 85 ends of such block, connections from such plates to the track under the control of such magnet, whereby the condition of the block may be automatically tested at such contact plate, an additional means at 90 each end of each block adapted to control the connection from the contact plate beyond the opposite end of that block to the track, and means whereby a moving locomotive or car may operate such additional 95 means.

13. The combination with a track divided into blocks, contact plates located beyond the opposite ends of the blocks, openable conductors from such contact plates to the 100 track, and mechanism located on opposite ends of the block beyond the contact plates and each operable by an approaching locomotive to open such connection to the contact plate beyond the opposite end of 105 the block.

14. The combination of a track divided into blocks, a track system including for each block a main circuit, with a relay, two line circuits, controlled by such relay, two 110 contact plates, connections between the same and the track controlled by said line circuits, and two protecting relays, one at each end of the block, each controlling such connection for the contact plate at the opposite end of 115 the block.

15. The combination of a track divided into blocks, a track system including for each block a main circuit, a relay therefor, two line circuits controlled by such relay, 120 magnets in such line circuits, armatures therefor, a contact plate at each end of the block, connections between the same and the track controlled by said armature, two exposed contacts at each end of the block, 125 and two governing relays, each controlling the line circuit which controls the connection for that contact plate which is at the opposite end of the block from the exposed contacts, each governing relay including a pair 130

of opposed magnets and a circuit for each magnet, the two exposed contacts being each adapted to be electrically engaged by a moving locomotive and included in the last mentioned circuit.

16. The combination of a track divided into blocks, contacts beyond the ends of the blocks, mechanism operable by a vehicle within the block for causing such contacts to give a danger signal to a locomotive engaging them, a line circuit operating on said mechanism for causing one of such contacts to give a danger signal, governing circuits for said line circuits including a portion of the track, whereby the said circuits are controlled by a locomotive before it enters the block, and means whereby such locomotive may control the governing circuit after it has entered the block.

17. The combination of a track divided into blocks, a main track circuit, two line circuits governed thereby, signals governed by the line circuits, and two pairs of protecting circuits, each pair governing one of the line circuits, and each circuit of each pair being itself governed by a passing locomotive or car and acting to open or close the line circuit.

18. The combination with a track divided into blocks, of mechanism at opposite ends of the blocks automatically controlled by a vehicle within the block for signally protecting the block at each end, mechanism controlled by a vehicle beyond the end of the block and co-operating with the first mentioned mechanism for signally protecting the block at the opposite end, and means for reversing the operation of such last mentioned mechanism after the block has been entered.

19. The combination of a track divided into blocks, a main track circuit, including a relay, conductors, a portion of the track, and a source of current, two line circuits controlled by such relay and having two magnets, means whereby such magnets may control signals for opposite ends of the block, and additional means opposite each end of the block for controlling the signal at the far end.

20. In an electric signaling system, the combination, with a track divided into blocks, of a governing relay adjacent to the entrance to a block, including a pair of opposed magnets, circuits for said magnets including a portion of the track, contacts connected with said circuits and with the track and adapted to be engaged by a passing vehicle, whereby the current through said circuits may be varied, one of such circuits having two of such contacts where its current may be so varied, and the other having one of such contacts located intermediately of the other two, such two points of variation of one of the magnets being located within

adjacent blocks respectively, and mechanisms for giving a signal controlled by said relay.

21. The combination of a track divided into blocks, signal-giving means beyond the opposite ends of each block, means within 70 a block and connections therewith for varying both signal giving means, and means in the adjacent block beyond the signal-giving means and extending over into the block under consideration and co-operating with 75 such connections for varying the signal beyond the other end of such block.

22. The combination of a track divided into blocks, a closed track circuit in each block, signal giving means adjacent to the 80 opposite ends of a block adapted to be rendered active by a vehicle bridging the rails within the block, and means beyond the far end of the block operable by a moving vehicle thereon and adapted to control the 85 signal giving means to give a danger signal at the opposite end of the block, such means beyond the far end of the block extending also into the block and being there operable in the reverse direction.

23. The combination with a railway 90 divided into blocks, of an electric signal installation including a main circuit for each block, two line circuits controllable by the main circuit, two relays, each relay being 95 adapted to also control one of the line circuits, each relay having associated with it two circuits, and means whereby a passing vehicle may vary such last mentioned circuits.

24. The combination with a railway 100 divided into blocks, of an electric signal installation including a main circuit for each block, two line circuits controllable by the main circuit, two governing relays, each relay being adapted to also control one of the line circuits, each relay having associated with it two circuits, each including a source 105 of current, and means whereby a passing locomotive may short circuit such source of 110 current.

25. The combination with a railway 115 divided into blocks, of a main circuit for each block including the track of a block, a relay, a source of current and conductors, 120 two governing relays for each block, each governing relay including a pair of opposed magnets and having associated with them two circuits for controlling such magnets, means for controlling such governing 125 circuits by a moving vehicle, signal means, and two line circuits for controlling such signal means, both under the control of the main relay, and each under the control of one of the governing relays.

26. In a signal system, the combination, with a track divided into blocks, of a track signal system including a main circuit for each block having a relay, two pairs of governing relays for each block, each pair 130

of relays having two operating circuits, two signal controlling devices for each block, and two line circuits for each block for controlling the signal-controlling devices, each line circuit being under the control of the main relay and one of the pairs of governing relays.

27. The combination, with a track divided into blocks, of signal controlling means, a main circuit having a magnet and a line circuit controlled by the magnet for each block adapted to operate the signal controlling means; a governing relay for each block, two circuits for controlling the governing relay, means whereby said circuits may be varied by a vehicle on the track, and means whereby the relay may vary the line circuit.

28. The combination with a track divided into blocks, of a vehicle circuit and a track system, said system including a main track circuit, two line circuits controlled thereby extending throughout the corresponding block and into the two adjacent blocks at opposite ends thereof, contact means controlled thereby and adapted to coat with the vehicle, a governing relay in each of such two adjacent blocks, each adapted to control one of the line circuits in addition to the control thereof by the main circuit, two circuits for varying each governing relay, connected across the track at different points, and batteries in said governing circuits adapted to be successively shunted out by the moving vehicle.

29. In an electric signal system, the combination of a railway divided into blocks, a signal means adjacent to one end of a block, and a governing relay adjacent to the other end of the block to vary such signal means, said relay having a pair of opposed magnets, and two circuits for operating them, each of such two circuits being adapted to be controlled by a passing vehicle.

30. In an electric signal system, the combination of a railway divided into blocks, a signal means adjacent to one end of a block, and a protecting relay adjacent to the other end of the block, and circuits controlled thereby adapted to vary such signal means, said relay having a pair of opposed magnets, and two circuits for operating them, each of such two circuits being adapted to be controlled by a passing vehicle, one of such circuits having two points of control on opposite sides of the control point of the other circuit, whereby a passing locomotive may operate first one circuit, then the other, then the first circuit.

31. The combination with a railway divided into blocks, of a main circuit, signal means at one end of the block, a governing device at the other end of the block, a line circuit controlled by said main circuit and governing device and extending therefrom beyond the opposite end of the adjacent

block, whereby the governing device can control the signal means at the far end of the block, such governing device including a pair of opposed magnets and a controlling contact member, and two circuits for controlling said magnets to cause opposite deflections of the contact member controlled thereby.

32. The combination, with a railway divided into blocks, of a main circuit including a magnet, signal-controlling means controlled thereby and a governing device also controlling the signal-controlling means, such governing device including a pair of opposed magnets and a contact member, and two circuits for controlling said magnets to cause opposite deflections of said contact member controlled thereby, one of said circuits having means whereby it may be controlled by a passing locomotive and the other of said circuits having two contact means adapted to be engaged by a passing locomotive to affect the circuit, said two means being located on opposite ends of the first means, and one of said two means being within a block adjacent to the block occupied by the rest of said means.

33. In an electric signal system, the combination of a track divided into blocks, a governing circuit located adjacent to the end of a block and connected with short exposed contact member of a rail, one within the block and one beyond the block and also connected with the other rail, such members being adapted to be connected by a passing vehicle with such other rail, a source of current shunted when such members are so connected with the other rail, and signal giving means controlled by the governing circuit.

34. In an electric signal system, the combination of a track divided into blocks, a relay associated with each block comprising a pair of magnets, a circuit for each magnet, a battery for each circuit, and means adjacent to the end of a block connected with such circuits and adapted to be engaged by a vehicle, whereby each battery may be short-circuited by a passing vehicle.

35. In an electric signal system, the combination of track rails, a main circuit, contact plates, connections from the contact plates to the rails which are under control of the main circuit, a governing relay also controlling one of such connections, and two circuits for operating the relay, said circuits being connected to different sections of the track rails.

36. In an electric signal system, the combination of track rails, a main circuit, contact plates adapted to be engaged by means on a locomotive, connections from the contact plates to rails which connections are under control of the main circuit, a protect-

ing relay also controlling such connections, two circuits for operating the relay in opposite directions, a source of current in each of said two circuits, said circuits having 5 connections at different points along the track whereby a passing locomotive or car may short-circuit such sources of current successively.

37. In an electric signal system, the combination of track rails, a main circuit, contact plates adapted to be engaged by means on a locomotive, connections from the contact plates to the rails which connections are under control of the main circuit, a protecting relay also controlling such connections, two circuits for operating the relay in opposite directions, a source of current in each of said two circuits, said circuits having connections at different points along the 20 track whereby a passing locomotive or car may short-circuit such sources of current successively, one of said two circuits having two places whereby it may be short-circuited, the place for short-circuiting the other 25 circuit coming between the two places mentioned.

38. In an electric signal system, the combination of a normally closed main circuit for each block, two line circuits for each 30 block controlled by the conditions of the main circuit and each extending over into the adjacent blocks, a governing relay for each line circuit, and means whereby a locomotive may actuate the governing relay before entering a block.

39. In an electric signal system, the combination of a main circuit, two line circuits controlled by the main circuit, a governing relay for each line circuit, two circuits for 40 each governing relay, and means along the trackway engaged by an approaching locomotive connected with said last mentioned circuits.

40. In an electric signal system, the combination of a main circuit, two line circuits controlled thereby, a governing relay for each line circuit including an armature and two opposed magnets, two circuits for said 50 two opposed magnets, said last mentioned circuits being connected with the rails at longitudinally separated points whereby a locomotive on the rails may cut out first one magnet and then the other.

41. In an electric signal system, the combination, with a main circuit and line circuits controlled thereby, of a governing relay for controlling one of the line circuits and having two opposed magnets, means on the trackway whereby the vehicle may short- 60 circuit one of said magnets, and two means

on the trackway straddling the means first mentioned and enabling the locomotive to short-circuit the other magnet.

42. In an electric signal system, a governing relay adjacent to the end of each block, 65 said relay having two magnets, and two means before the entrance to the block for controlling the magnets, respectively, and one means after the entrance to the block for controlling one of said magnets. 70

43. In an electric signal system, the combination, with a main circuit, of a line circuit controlled thereby, a governing relay for controlling the line circuit, and means whereby a vehicle approaching and entering 75 the block corresponding to the main circuit may operate the governing relay first in one direction, then in the other direction, and then after entering the block operate it in the first direction. 80

44. The combination, with a track divided into blocks, of a main circuit and magnet and a line circuit governed thereby for each block, a governing relay for controlling the line circuit, track connections 85 for controlling the relay, said track connections being located at three points, two or them in advance of each block and one within the block.

45. In an electric signal system, the combination, with a track divided into blocks, 90 of suitable circuits and magnets and means operated thereby to give an indication, a governing relay for governing the condition of said circuits for each block and three 95 track arrangements for operating the relay, two of such arrangements having contact members located in advance of the block whose circuits the relay governs and the third having a contact member located within 100 such block.

46. The combination, with a railway divided into blocks and suitable signal devices and circuits, of a governing relay for governing one of such circuits and having a 105 pair of opposed magnets, circuits and batteries for said magnets, means whereby the wheels and axles of a vehicle may short-circuit one of said magnets, and two means whereby the wheels and axles of a vehicle 110 may short-circuit the other magnet, said two means being located one in front of and the other behind the means first mentioned.

In testimony whereof, I hereunto affix my signature in the presence of two witnesses. 115

ELMER M. JONES.
